UNITED STATES PATENT OFFICE.

JOHN R. LONG, OF AKRON, OHIO, ASSIGNOR, BY MESNE ASSIGNMENTS, TO WILLIAM A. BYRIDER, OF AKRON, OHIO.

BENCH-VISE.

1,113,663.

Specification of Letters Patent.

Patented Oct. 13, 1914.

Application filed October 27, 1913. Serial No. 797,613.

To all whom it may concern:

Be it known that I, JOHN R. LONG, citizen of the United States, residing at Akron, in the county of Summit and State of Ohio, 5 have invented certain new and useful Improvements in Bench-Vises, of which the following is a specification.

This invention relates to an improvement in bench vises, and the invention consists in 10 the construction and combination of parts substantially as shown and described and particularly pointed out in the claims.

In the accompanying drawings, Figure 1 is a side elevation of the vise shown with 15 the jaws open. Fig. 2 is a rear end elevation, and Fig. 3 is a front elevation with the operating handle omitted. Fig. 4, sheet 2, is a side elevation partly in section with the jaws closed on an object therein. Fig. 5 is a cross 20 section on line 5—5, Fig. 4.

The present invention has to do more especially with certain important details of construction relating to the automatic locking of the vise when in use and the construction 25 of the bar which supports the slidable jaw and the yoke, and is an improvement upon the vise shown and claimed in my application filed February 10, 1913 and bearing Ser. No. 747,214. The main parts are 30 substantially the same in both cases and comprise a base A, adapted to be firmly fixed upon a bench, block or other support, a main or fixed jaw C rotatably engaged on said base, a slidable or movable jaw D, supporting bar B and yoke E. The said base is 35 substantially dish shaped so as to be open on its bottom to place the pivot screw 2 in position for engagement of the friction member or disk 3 thereunder and with the shank of 40 jaw C, the said shank having a screw threaded hole from beneath penetrated by said screw and which serves to hold the said jaw C in horizontal rotatable position on the otherwise flat top of said base.

45 The shank of the jaw C lies in the channel between the cheeks 6 on the friction member 3 and rests upon the collar 5 on the top of the base and which fits closely about said cheeks, thus making a close fit to prevent 50 particles from working through to the inside and also making a striking portion over the said base to protect the same from injury, the said base being of cast metal and liable to be cracked or broken by a blow directly 55 thereon. The said cheeks 6 have straight

parallel walls fitting closely upon or against the said shank 7 of jaw C, and it follows through this construction that when said jaw is rotated on base A the said friction member 3 is rotated therewith.

In operation it is intended that the pivot screw 2 shall be made sufficiently tight to merely hold the jaw C from being rotated, and such rotation is only intended to bring the tool into convenient position for use and according to the conditions about it for use. Then when positioned as desired the actual locking against rotation during use is provided for through the means at the heel 8 of the shank 7 on jaw member C. These means 60 comprise a transverse bolt or screw 9 through the bifurcated or open slotted upward extension 10 of the jaw shank 7 at the end thereof and which is provided with a transverse hole for said bolt 9. The supporting bar B for 65 jaw D and yoke E has a flaring transverse recess or opening in its larger and outer end which is traversed by bolt 9 and which serves as a rest for the said bar in said recess, and said bar has a limited lengthwise sliding 70 movement on said bolt 9 at its rear and on its spindle 12 at the front, thus serving to lock 75 said jaws on the work after the jaw D has been moved into engaging or clamping position, say as seen in Fig. 4. Such lengthwise 80 movement or adjustment of bar B is by means of the screw S which engages in the internally threaded stem 12 projecting 85 through a corresponding bore in the base of jaw C. The said screw has a head carrying 90 the operating rod or handle 14, slidably therein and by which a very limited lengthwise tightening movement of bar B is provided for to take up any slack or looseness 95 after the jaw D and yoke E have been moved up by hand to engaging position. Such movement or handling is in part provided for by the hand knobs 17 on the side of the yoke, adapted for both right and left handed persons. The said parts D and E are operatively connected by the set screw 17 entering 100 a side recess in said jaw. By gripping one of said knobs the jaw D can be moved back and forth through the movement of the yoke. This done and the jaw moved up to 105 the work as in Fig. 4, the tightening of the parts is effected through screw S. Incidentally this also locks the bar B against rotation on pivot 2 because it tends to tilt the heel 8 upward and to depress the correspond- 110

ing end of bar B by the opposite effect upon 5 jaw D. Actual locking between the parts as against rotation horizontally on the base occurs through a set screw 18 engaging in a thimble or bushing 19 in a cavity within heel 8 and adapting the clamping effect upon the stock held by the vise to react upon said set screw and said thimble and lock the bar B against rotation. The said thimble bears 10 on collar 5 and the end of bar B bears on the head of set screw 18 in its flattened portion which comes slightly above the top of the bottom of the slot in or between the extensions 10. The said screw enables me to make 15 refined adjustments to take up possible wear at this point as well as to provide an exposed bearing for the thimble 19, but when the jaws are released tension on screw 18 also is relieved.

20 A further material improvement in the present vise over the above application resides in the shape of the top bearing surface of bar B for the yoke E. In the above mentioned application the said bar is shown as 25 being flat transversely on its top but in the present instance I have made the said surface of inverted V shape, thus providing a riding edge 20 for the jaw D which has correspondingly inclined sides guided thereon 30 and this serves also to keep the top of the said bar clear from foreign accumulations.

35 A further improvement is found in the clip 22 adapted to be engaged over the rear end of bar B and to seat at its sides upon the top edges of the upward extensions 10 on the shank of jaw C. The said edges are straight and correspond to the side edges of the clip resting thereon, and a lifting screw 23 engages through the top of said clip and 40 into a threaded hole in the end of bar B. When the said screw is tightened it has a lifting action or effect on bar B and to this extent relieves down pressure on the screw 18 and enables the vise to be rotated on its base without releasing the stock gripped 45 therein by turning the screw S, as would be necessary if the said clip were not employed. Releasing screw S would also release the stock, but by means of said clip 50 the stock can be kept in the vise and the vise rotated. The yoke E is flared from rear to front to engage with locking effect on both bar B and jaw D, and the bottom b of bar B is inclined upward from rear to front and the back d of jaw D is at a somewhat 55 greater inclination rearward and downward according to the top flare in said yoke so that when the said yoke and jaw are moved to clamping position the jaw will be effectively locked and cannot slide away under pressure. By making the inclined edge b less than 45 degrees as shown and placing the yoke in a more or less tilted relation this locking is made very effective. 60

65 The said cheeks 6 represent the top exposed

sides of the hub on the said friction member 3, and the said hub is circular or round and fits in the circular opening in the base so as to be rotatable therein, and the said collar 5, a sheet metal part, preferably fits 70 snugly about its inner edge upon said hub above base B. The jaw D has a collar or bead d' about its neck adapted to divert any filings that may fall about the jaw from work held in the jaws from falling on the 75 base, or sliding against and working under the yoke E, and thus interfering with adjustments.

The construction of yoke E and the bar B and jaw D are such that when the said jaw 80 is released or loosened from work and drawn back the yoke E will not only become loose also but drop down and rest on the top edge of the shank 7 of jaw C. The heavy transverse bolt 9 through the ears 10 of the outer 85 jaw member C serves more especially as a back stop for the jaw D. Of course the vise can be used without the clip 22, but said clip is very useful when the work is heavy and there is need of swinging the vise 90 around in either direction before the work is released from the jaws. In that case the said clip takes the pressure off of the bolt 19 sufficiently to enable the vise to be rotated on base A. By the term "bolt" I 95 mean the two parts 18 and 19, because a single solid bolt will serve my purpose but I use a two-part bolt by preference so as to have an adjustable portion to take up wear thereon.

100 What I claim is:

1. In vises, a base of substantially dish shape having a flat top and a down flange about its edge and an opening in its center, a friction member inserted from beneath 105 through said opening and bearing against the bottom of said base and provided with cheek portions projecting through said opening and provided with a channel between them, in combination with a jaw having a shank seated in said channel between said cheeks and a screw through said friction member and engaged in said shank and adapted to lock said parts together upon 110 said base.

115 2. A vise having a base and a friction member rotatable in said base having a hub, an outer jaw having a shank fixed in said hub, a bar supported at one end on the rear end of said shank and provided with a spindle engaged through the base of said jaw, an inner jaw slidably mounted on said bar and a yoke connecting said inner jaw operatively with said bar.

120 3. A vise having a base, a friction member 125 rotatably mounted in said base and provided with a walled channel exposed above the base, an outer jaw having a tapered shank locked in said channel through said friction member, in combination with an 130

inner jaw, a bar on which said inner jaw is slidably mounted and supported at one end on an upward extension of said shank and at the other end in the base of said outer jaw, means to draw said bar lengthwise to tightened position and a bolt under the heel of said bar bearing down upon the said base and adapted to lock the vise against rotation when it is engaged upon an object.

10 4. In a vise, an outer jaw having a tapered shank and an upturned outer extremity and a base on which said jaw is rotatably mounted, a bar having one end supported on said extremity and provided 15 with a spindle at the other end projected through the base of the jaw and internally threaded, a rotatable tightening screw engaged in said spindle and a bolt in the rear of said shank adapted to lock said bar 20 against rotation on said base, and an inner jaw slidably confined upon said bar.

5. A vise as described having an outer jaw member having a shank provided with an upturned divided outer end, a jaw supporting bar mounted at both ends on said jaw member and removably supported thereon, an inner jaw adjustably mounted on said bar and a yoke about said inner jaw confining the same operatively on said bar, 25 in combination with a base supporting said jaw member, a locking bolt in the heel of said bar bearing upon said base and a screw 30 in said bolt to take up wear.

6. A vise having a bar and an outer jaw

adjustably mounted thereon and provided 35 with a split upwardly turned end and a transverse bolt in said end, in combination with a bar mounted on said bolt and having a spindle projected into the base of said jaw, a clip seated over the end of said bar 40 and resting at its sides on the sides of said upturned end and a screw through said clip and engaged in said bar and adapted to lift the bar and thus relieve the said outer jaw from pressure upon said base. 45

7. A vise comprising a centrally mounted bar having a rearward taper defined by a horizontal top edge of inverted V-shape cross section and an upwardly inclined bottom edge, in combination with an inner jaw 50 having a substantially V-shaped channel in its bottom edge, slidably mounted on said inverted V-shaped top edge, and a yoke operatively confining said parts together.

8. A vise of the kind described having an 55 outer jaw, and a suitable support on which said jaw is slideable, and a yoke operatively confining said parts together, said jaw being provided with a bead about the neck thereof adapted to shed filings from its 60 sides and prevent the same from falling upon said support and yoke.

In testimony whereof I affix my signature in presence of two witnesses.

JOHN R. LONG.
